UNITED STATES PATENT OFFICE.

JOHN THOMAS BATTIS, OF GRAND RAPIDS, MICHIGAN.

ENDLESS-CARRIER GARMENT-SUPPORTING STRUCTURE.

Application filed July 19, 1920. Serial No. 397,195.

To all whom it may concern:

Be it known that I, JOHN THOMAS BATTIS, a citizen of the United States of America, residing at Grand Rapids, in the county of 5 Kent and State of Michigan, have invented certain new and useful Improvements in Endless-Carrier Garment-Supporting Structures; and I do hereby declare the following to be a full, clear, and exact description 10 of the invention, such as will enable others skilled in the art to which it appertains to make and use the same.

This invention relates to endless carrier garment holding constructions by means of 15 which an exceptionally large number of garments may be carried on hangers on rods which are mounted in properly spaced apart relation on carrier chains, the same being operable to bring the garments on any particular or selected rod into position for access and examination. It is a primary object and purpose of the present invention to make a device of this character in practical form so that it will effectually carry 20 the garments, be easily operable without binding or cramping of the mechanism in any way, be available for the holding of different lengths of garments such as suits of clothes or overcoats or like garments of 25 greater length, and which will occupy the minimum space consistent with the large quantity of garments it will carry and display. Many subsidiary objects and purposes for the effectual attainment of these 30 ends, and novel constructive details and arrangements of parts directed thereto will appear fully and in detail as understanding of the invention is had from the following description, taken in connection with the 35 accompanying drawings, in which,

Fig. 1 is a side elevation of an endless carrier garment holding construction made in accordance with my invention.

Fig. 2 is a front elevation thereof.

Fig. 3 is a horizontal section therethrough taken on line 3—3 of Fig. 1 above the driving mechanism of the construction.

Fig. 4 is a fragmentary vertical section at one side of the construction having to do with the detail of connecting or disconnecting a motor drive to the carrier.

Fig. 5 is a vertical section through a modified construction.

Fig. 6 is a front elevation thereof.

Fig. 7 is a fragmentary section similar

to that shown in Fig. 5, showing a different drive mechanism.

Fig. 8 is a sectional detail of the connection of the garment carrying rods to the chain carriers.

Fig. 9 is a front elevation of a slightly modified form of construction.

Fig. 10 is a vertical section therethrough.

Fig. 11 is a fragmentary inner side view 65 illustrating the means of adjustably mounting the equalizing shaft of the construction shown in Figs. 9 and 10.

Fig. 12 is a horizontal section on the plane of line 12—12, of Fig. 11, and

Fig. 13 is a side elevation of an installation 70 of the carriers of my invention in a store.

Like reference characters refer to like parts in the different views of the drawings.

In the construction, a supporting frame 75 including corner uprights 1 spaced apart at front and rear as shown in Fig. 3 is used, lower and upper side bars 2 and 3 connecting the side uprights at their lower and upper ends with intermediate side bars 4 and 5 disposed between the uprights at the side of the frame, the former being spaced a short distance above the latter. In addition, each side of the frame includes two uprights 6 paralleling, and a short distance back and 80 in front of, the front and rear uprights 1, respectively, disposed between the side bars 3 and 4, while short pieces or blocks 7 are disposed between the bars 4 and 5 directly under the lower ends of the uprights 6. 85 Lower and upper cross bars 8 and 9, at front and rear connect the sides of the frame and complete the same making a strong and substantially rigid structure.

Wheels 10 around which endless chains 11 95 run are mounted one on the inner side of each block 7 and one near the upper end of each upright 6. Each side of the supporting frame accordingly supports an endless carrier chain. A plurality of rods 12 is located 100 horizontally in substantially equally spaced apart relation between the pair of chains. Metal clips 13 are bent around sides 11 of certain links of the chains, the ends of the clips being brought together and secured 105 to plugs 14 inserted in the ends of the rods 12, suitable screws 15 passing into the plugs. The rods 12 are either tubular or bored out at their ends to receive the plugs. In this manner the rods are securely connected to 110

the chains at their ends and are adapted to carry a large number of garment hangers on which garments may be suspended. The end garments on a rod are guarded from contact with the chains by flat guards 16 which may be hooked over the rods as shown.

A shaft 17 passes through and has bearing in the cross bars 4, one end thereof having a worm wheel 18 fixed thereon. A worm shaft 19 is in mesh with the wheel 18 and is driven by a belt 20 passing around the drive pulley of an electric motor 21 and a pulley 22 fixed on shaft 19. A second shaft 23 lies below shaft 17 parallel thereto, being mounted at its ends in bearings carried by the bars 5. A combined sprocket wheel and clutch member 24 is loosely mounted on shaft 23 near one end thereof and is driven by a chain 25 which passes around the same and a sprocket wheel on shaft 17. A coacting clutch member 26 is splined on shaft 23, being operated into and out of engagement with clutch member 24 through a link connection 27 pivoted to an arm 28 at the rear end of a rock shaft 29 mounted at one side of the frame and extending to the front thereof where it is provided with an operating handle 30 as shown.

A sprocket wheel 31 is secured adjacent each end of the shaft 23 serving to drive sprocket chains 32 which pass around sprocket wheels 33 connected one to each of the lower front chain carrying wheels 10. It is evident that shaft 23 serves as an equalizing shaft for driving chains 11 at equal speed obviating any binding or cramping of the parts or distortion of the rods 12 from the horizontal. This is true whether the chains are motor driven or otherwise. When the clutch parts 24 and 26 are connected, the motor is connected to drive the chains 11 in endless flight. When disconnected, the chains may be driven through the medium of a crank 34 at the front of the frame which is attached to a rod 35 leading back to shaft 23 as shown in Fig. 1. Furthermore this connection of rod 35 to the shaft may be a detachable one so that the chains may be operated by grasping a rod 12 and drawing down on the same without reference to either the motor or the crank 34.

In Figs. 5 and 6 a modified construction is shown. The uprights 1 are set closer together from front to rear, the uprights 6 eliminated and cross pieces 4^a and 5^a located farther apart than the bars 4 and 5 of the former construction. Chain carrying wheels 10^a are mounted adjacent the upper ends of the uprights 1 and also a distance above the bar 4 on which a bearing for an equalizing shaft 36 is secured. The shaft reaches across from one bearing at

one side to the other and has a chain carrying wheel 10^b secured near each end thereof. Also on the shaft near each wheel 10^b a sprocket wheel 37 is fixed.

Directly below each of the wheels 10^b other similar wheels 10^d are mounted on stud shafts carried by the side bars 5^a. Sprocket-wheels 38 are connected with the wheels 10^d and chains 39 pass around the sprockets 37 and 38 at each side of the supporting frame. Other wheels 10^c similar to wheels 10^a are mounted on the uprights 1 above the wheel 10^d a distance substantially equal to the distance of wheels 10^a above the wheel 10^b.

With this construction, the chains 11 when around the wheels 10^a and 10^b are adapted to carry longer garments such as overcoats or the like, the rods 12 being spaced farther apart and the wheels 10^b being high enough above the bottom of the frame to permit lower ends of the garments to clear the same. The chains may be driven by any suitable drive for the shaft 36, which, if desired may be driven in the same manner as shaft 23 in the first construction. If shorter garments are to be carried, additional lengths may be added to the chains to permit the same to run around the lower wheels 10^c and 10^d, the drive being still from the equalizing drive shaft 36 as is evident. This permits the interchanging of the structure for shorter length garments to longer or vice versa. For the longer garments with the rods 12 farther apart, longer end guards 16^a are used. Furthermore with the driving wheels 10^b or 10^d for the chains located below the lower wheels 10^a and the wheels 10^c as shown, the chains are compelled to pass more around and have greater and more efficient engagement with said driving wheels, as is obvious, obviating any possible slippage of the chains and insuring a positive and equal drive of the chains on both sides.

Fig. 7 instead of using the sprocket chains 39 and wheels 37 and 38 makes use of bevelled gears 40 on the driving wheels 10^b and 10^d and mounts a vertical shaft 41 with bevelled pinions 42 thereon in engagement with the bevelled gears, the drive being the same in effect as that shown in Fig. 5 and the construction being equivalent in all functional respects.

In Figs. 9 to 13 inclusive, a preferred form of frame construction is disclosed. For the structures installed against a store wall, the rear vertical uprights 1^a will be perpendicular to the floor but the front members 1^b will be inclined upwardly and outwardly. Between the same at each side intermediate vertical uprights 43 are used on which to adjustably mount the lower drive shaft and chain driving wheels. The constructions placed out from the walls have both sides

inclined upwardly and outwardly so that the supporting frame is wider, even than the wall constructions, at the top than at the bottom. The remaining frame members 2^a, 5 3^a, 8^a and 9^a are like the parts similarly numbered 2, 3, 8 and 9 in the previously described constructions. Two upper chain carrying wheels 10^e are mounted at each side and at the upper part of the frame, being comparatively 10 widely separated. On the inner side of each upright 43 a metal plate 44 is permanently secured, having an inwardly pressed raised central portion 45 in which a plurality of key-hole slots 46 is cut one over the other. A shaft 47 extends between the uprights having chain drive wheels 48 thereon one at each end of the shaft. Said shaft is formed at each end with a head 49 adapted to enter the wider part of a slot 20 46, thence dropping down behind the part 45 at each side of the narrower portion of the slot, retaining the shaft in position against displacement. The shaft may be adjusted to different positions and the chains 11 going 25 therearound on the wheels 48 and 10^e shortened or lengthened as the case may be for different lengths of garments. Rods 12 may be differently placed also as is evident. Shaft 47 may be driven in any suitable manner and I have shown a sprocket wheel 50 thereon as indicating one way the power may be applied thereto through a sprocket chain from any suitable motor or other source of power.

35 From the foregoing description it is evident that I have made an improved endless carrier garment holding construction, one in which the chains at each side of the supporting frame are driven in unison, without 40 binding or cramping of the parts in any manner, one in which the construction may be adapted for different lengths of garments, the length of the chains being readily changed, and provision made for the clearing 45 of the floor by any of the garments irrespective of their length, and one in which a sure and positive drive of the carrier chains is had. In addition, the formation of the supporting frames as illustrated in Figs. 9 to 50 13 inclusive permits the spreading of the chain carrying wheels at the upper part of the frame where such additional width is necessary for the free passage of the garments, and a narrowing of the frame toward the bottom permits the economy of floor 55 space in stores since the wider upper parts of the supporting frame are above the space occupied by customers and salesmen and is

not needed. It is designed that these supporting frames with the garment carrying rods may go in suitable cabinets or cases in stores and an exceptionally heavy line of garments carried for the space occupied.

The invention is defined in the appended claims and I consider myself entitled to all 65 modifications in structure which may vary from the specific disclosures made but which come within the scope of the claims.

I claim:

1. In combination, a supporting frame 70 having spaced apart sides, an endless chain mounted on each side of the frame, tubular rods disposed in spaced apart relation between the chains, a plug inserted in each end of each rod, a metal clip bent upon itself around certain of the links of the chain at the ends of the rods, and securing means passing through the ends of the clips and into the plugs in the ends of the rods.

2. In combination, a supporting frame 80 having spaced apart sides, a pair of spaced apart wheels rotatably mounted adjacent the upper end of each side of the frame, a single larger wheel rotatably mounted at a lower part of each side of the frame, a shaft connecting said lower wheels and to which said wheels are fixed, and means attached to each side of the frame with which the ends of said shaft are adapted to have detachable connection at a plurality of spaced apart 85 points, said chains being lengthened or shortened to correspond with the change of position of the shaft.

3. In combination, a supporting frame 95 having spaced apart sides, and being wider at the top than at the bottom, two spaced apart wheels carried adjacent the upper end of each side of the frame, a shaft located below the upper wheels and extending between the sides of the frame, a plate attached vertically on each side of the frame and formed with a series of key-hole slots one over the other, said shaft being formed with heads at the ends thereof to engage in said slots, relatively large wheels on the 100 shaft, one at each end thereof, chains passing around each large wheel and upper pair of wheels at each side of the frame, said chains being formed of links and capable of being lengthened or shortened, and article 105 carrying bars disposed between the chains in spaced apart horizontal relation and detachably connected to the chains at their ends.

In testimony whereof I affix my signature.

JOHN THOMAS BATTTS.
